NORMAN H. RICKER, OF HOUSTON, TEXAS, ASSIGNOR TO HUGHES TOOL COMPANY, OF
HOUSTON, TEXAS, A CORPORATION OF TEXAS

PNEUMATIC SWAB

Application filed October 27, 1930. Serial No. 491,341.

- My invention relates to pneumatic swabs and pertains particularly to the structure of the standing valve controlling the inlet of liquid to the lower end of the eduction tube. It is an object of the invention to provide a standing valve which will allow the entrance of liquid to the eduction tube while the pressure fluid is being discharged into the lower end of said tube. I desire to provide a standing valve which may be secured in position to provide an injector through the action of the pressure fluid, and thus assist in raising the head of liquid in the eduction tube above that of the liquid in the well. My valve is constructed to close to prevent back pressure of the pressure fluid into the well but to open when the back pressure is released to allow the liquid to enter freely into the eduction tube. This invention is a modification of that disclosed in my co-pending application No. 488,565, filed October 14, 1930. In the drawings Fig. 1 is a longitudinal section of the upper end of the well swab apparatus and Fig. 2 is a similar view of the lower end thereof, with my invention embodied therein. Figs. 3 and 4 are transverse sections taken on the planes 3-3 and 4-4 respectively, of Fig. 2. Fig. 5 is an enlarged detail of the lower end of the swab plunger. An apparatus upon which my invention may be used is shown in the drawings. There is an outer casing 1 connected at its upper end to a casing head 2 formed with an outlet 3 for the liquid being pumped. There may also be a gas relief pipe 4 in the head and a gas inlet pipe 5. At the upper end is a bushing 6 having an elongated bull plug or cap 7 therein to close the upper end of the casing and house the upper end of the eduction tube. Within the casing is an air inlet pipe 8 and a smaller concentric eduction tube 9. The pipe 8 is suspended at its upper end from a block 10 supported in the casing head and reduced at its upper end 11 for connection with the extension 12 closed at its upper end 50 by the shock absorbing cap 13. Slotted out lets 14 in the port 11 allow an exit for the liquid and air. The block 10 has a peripheral channel 15 connected with the gas and air inlet 5, and has passages 16 to the interior space 17 for the entrance of pressure fluid. The lower end of the pipe 8 has a foot member 18 formed on its interior with a shoulder 19 to support the lower end of the eduction tube 9, and a tapered seat 20 below said shoulder leading to the inlet passage 21. The lower end of the foot member has a strainer 22 secured thereto, if desired. The eduction tube has a seat 23 at its upper end within the block 10 and has a head at its lower end fitting within the pipe 8. Said head has longitudinal passages 23^a allowing flow of gaseous fluid to the interior of the tube at 24. There is a plurality of such air inlets as seen in Fig. 4. Spaced between the air inlets are upward passages 25 for liquid leading to inlet ports 26 to the interior. Within the eduction tube is a standing valve housing 27 connected at its lower end to the plug 28 formed to fit the seat 20 and support the housing. It has an interior valve seat 29 to receive the ball valve 30. The interior of the housing is divided into an upper chamber 31 and a lower valve chamber 32 by a transverse partition 33. The valve chamber 32 has an outlet 34 connecting with the liquid conducting passage 25. There is an air inlet port 35 from the passage 23^a to the chamber 31. The upper part of the chamber 31 tapers to a plunger seat 36 above which it widens out at 37 to form a venturi passage for the pressure fluid. The liquid from the passage 25 may enter into the chamber 37 through the passage or passages 38. The standing valve housing 27 is held in position by means of a locking collar 39 having its lower edge flared outwardly to wedge about the upper tapered end of the housing. The swab plunger 40 fits within the eduction tube. Its lower end is reduced in diameter to form a support for the valve member 41 which is normally held from its seat 42 by gravity. A stem 43 on the valve fits within a guide member 44 at the lower end 100

of the plunger. Said guide has a tapered end to fit the seat 36 and its lower extremity is closed by a rounded plate 46 as seen in Fig. 5. In the sides of the guide above the plate 46 are inlet openings 47 for liquid below the valve.

In operation, the swab plunger will start up from its position as seen in Fig. 2, by the entrance of pressure fluid by way of the passage 17, the port 24, to the chamber 31, closing the valve 41 and lifting the plunger from its seat. The passage of pressure fluid out the lower end of the apparatus will be prevented by valve 30. When the load of liquid above the plunger is discharged through the outlets 14 and 3, the plunger will be stopped by the fluid compressed in the extension 12, and the valve will be forced open. The air will exhaust below the plunger, and the plunger will start on its drop to the bottom.

When the exhaust of air through the outlet 3 takes place, the pressure above valve 30 will be released, and the valve may open to allow inlet of oil or other liquid. Also the air entering through the Venturi passage 37 will act as an injector drawing the liquid in rapidly. Said liquid will rise to a level above that of the liquid in the well, and when the plunger approaches its seat it will pass through this liquid and will be slowed down to prevent its striking the seat 36 with force. When the seat has been reached, the pressure fluid will soon act to again close the valve 41 in the plunger and repeat the operation.

It will be seen that my device may be used with or without a pressure fluid regulator and will act to draw in a head of liquid above the plunger to a level higher than that in the well, and I will be able to operate the device economically in wells where the head of liquid is not great.

My standing valve may be withdrawn from the well by a fishing tool, first withdrawing the locking collar 39, and then engaging and withdrawing the valve housing itself.

What I claim as new is:

1. A pneumatic swab device including an eduction tube, a standing valve housing at the lower end of said tube, upper and lower chambers in said housing, an upwardly opening valve controlling an inlet opening to said lower chamber, a pressure fluid inlet to said upper chamber, a Venturi passage from said upper chamber, a plunger adapted to close said passage, and a by-pass for liquid from said lower chamber to said plunger.

2. A pneumatic swab device including an eduction tube, a standing valve housing at the lower end of said tube, upper and lower chambers in said housing, an upwardly opening valve controlling an inlet opening to said lower chamber, a pressure fluid inlet to said upper chamber, a Venturi passage upwardly from said upper chamber, a plunger adapted to seat in said passage and a by-pass from

said lower chamber into said Venturi passage above the plunger seat.

3. A device of the character described including an eduction tube, a valve chamber at the lower end thereof, a pressure fluid inlet chamber above said valve chamber, a Venturi passage from said fluid inlet chamber, a plunger adapted to seat in said passage, and means to conduct liquid from said valve chamber to the upper end of said passage.

4. A device of the character described including an eduction tube, a valve chamber therein, a valve in said chamber, a plunger in said tube, an inlet for pressure fluid below said plunger, a by-pass for liquid from said lower chamber to the lower end of said plunger, and an injector for moving said liquid upwardly in said tube.

In testimony whereof, I hereunto affix my signature, this the 22nd day of October A. D., 1930.

NORMAN H. RICKER.
